EDWIN FITCH NORTHRUP, OF PRINCETON, NEW JERSEY

METHOD AND APPARATUS FOR PRODUCING LIGHT

Application filed June 11, 1930. Serial No. 460,531.

My invention relates to methods and apparatus for producing light.

The principal purpose of my invention is to combine the advantages of an electric incandescent lamp and of a glow lamp.

A further purpose is to secure a high difference of potential between electron-emitting filaments fed from the same high frequency preferably low voltage source.

10 A further purpose is to heat two separate lamp conductors preferably to luminescence by passage of alternating current through them and to connect them through reactance to provide a high voltage drop between them, resonating the circuit to secure maximum effectiveness and using high frequency to reduce the capacity required for a given reactance.

20 A further purpose is to utilize high frequency current for the purpose of producing light under conditions of desirable economy.

A further purpose is to obtain light on a commercial scale by the bombardment of an electron emission from a hot body against 25 the molecules of gases and solids.

A further purpose is to light a lamp from a circuit in which the conditions of series resonance obtain.

30 A further purpose is to produce light by maintaining a high potential difference between two or more hot bodies.

A further purpose is to connect a plurality of heated elements contained within a closed lamp to a source of alternating current.

35 A further purpose is to maintain a potential difference from an alternating source between a plurality of electrically heated elements surrounded by a vacuum or by a special gaseous atmosphere.

40 A further purpose is to electrically heat a plurality of incandescent lamp filaments contained within a lamp, and to add to the light-giving qualities of the filaments the glow produced by the luminescence of gases contained in the lamp, due to electron emission 45 from the filaments.

A further purpose is to construct combined incandescent and glow lamps which may be connected to a common current source in series or in parallel.

Further purposes will appear in the specification and in the claims.

My invention relates both to the methods or processes involved and to structure by which the methods or processes are carried out.

I have preferred to illustrate my invention by a few embodiments only of the same general form, selecting embodiments which are effective and fully operative but which have been selected primarily because of their suitability for illustration of the principles involved.

In the drawing like numerals refer to like parts throughout.

Figure 1 is a diagrammatic representation of lamps A and B embodying my invention connected in parallel to a common current source.

Figure 2 diagrammatically indicates the connection of a plurality of my lamps in series, E, the series being itself in parallel with a lamp C and a lamp D.

Figure 3 diagrammatically illustrates a conventional series circuit containing resistance, inductance, and capacity.

Figure 4 is a vector diagram for the circuit of Figure 3, assuming arbitrary values for the resistance, inductance and capacity.

Figure 5 is a vector diagram for the circuit of Figure 3 under the conditions of series resonance.

Figure 6 shows a lamp embodying my invention in which the electron-emitting bodies are heated by separate current sources, and a voltage drop is maintained between them by series resonance in another circuit.

The development of the audion tube has served to familiarize the art with the phenomenon of electron emission from a hot body, particularly when that body is connected to the negative side of a direct current source, and the positive line from the source is connected to an element maintained adjacent to the hot body and within the tube. I propose to apply this phenomenon to increase greatly the light-giving effectiveness of an electric lamp.

I operate my lamp from an alternating cur-

rent source, and am thus able to employ a plurality of hot bodies within the electric lamp. Considering for the present only a single phase source, I will use two hot bodies within the lamp, one connected to each side of the current source, so that the direction of electron flow from or toward either body will reverse with the reversals of the current.

It would of course be possible to maintain the temperature of the hot bodies by connection to current sources local to each of them, as is done in the familiar "A" battery circuit of the audion tube. This would, however, be complicated, expensive, and inefficient, and therefore I prefer to maintain the temperature of the hot bodies by RI^2 heating from the line current. I do not pass the line current directly from one of the hot bodies to another, because this would prevent the maintenance of a high voltage drop between them, such as is essential to the production of light from electron bombardment.

While I intend to maintain a considerable voltage between the heated bodies in the lamp, I plan to avoid distributing high voltage current in a building in which the lamp may be employed.

I find that it is possible to secure a high voltage drop across the heated bodies within the lamp from a low (commercial) voltage source provided I meet the conditions of series resonance in the lamp circuit. I show a supposed condition of regulation for the circuit of Figure 3 in the vector diagram of Figure 4, corresponding to arbitrarily chosen values for the voltage drops across the resistance, inductance and capacity, respectively E_R , E_L , and E_C , with the assumed current value I . It is there seen that the current lags the voltage E by the angle α , so that the power factor regulation will be poor.

If the circuit be resonated, however—that is, if the inductive reactance and the capacitative reactance be made equal—the power factor will become unity. Obviously, under this condition, the voltage drop E_C across the capacity will equal the voltage drop E_L across the inductance, and the line voltage will equal the voltage drop E_R across the resistance, merely. This is apparent from Figure 5.

Thus a very high voltage drop may be maintained across the inductance, although the line voltage is low.

With the usual line frequency, such as 60 cycles for example, the size of the inductance coil or of the condenser required to maintain resonance would be prohibitive from a commercial standpoint. However, at high frequency, the circuit may be resonated by the use of very little inductance for a given capacity. This may be understood by expressing the frequency f under the conditions of resonance in terms of the coefficient of self-induction L and the capacity C . For reso-

nance the inductive reactance X_L must equal the capacitative reactance X_C . Now

$$X_L = 2\pi f L$$

$$X_C = \frac{1}{2\pi f C}$$

(Gray, "Principles and Practice of Electrical Engineering," McGraw Hill Company (3d ed. 1924) 213, 227). During resonance

$$2\pi f L = \frac{1}{2\pi f C}$$

$$L = \frac{1}{4\pi^2 f^2 C}$$

For any given capacity, the size of the inductance coil required to resonate the circuit is inversely proportional to the square of the frequency.

Thus by far the greatest advantage from my invention is to be derived by operation on high frequency current preferably at about 1000 cycles. A considerable by-product advantage will be obtained because my lamps may operate from circuits designed for high frequency induction furnace operation or for other uses.

Referring now to Figure 1, I there show a source of alternating current 10 supplying current to lines 11 and 12 at any suitable voltage, for example, at 220 volts. In lamp A, the lamp body 13, constructed of glass or any other suitable transparent or translucent material, contains the hot electron-emitting bodies 14 and 15, attached to terminals 16, 17, 18 and 19 extending through the glass wall.

The lines 19 and 20, extending from opposite sides of the supply mains 11 and 12, are connected respectively to one side of the reactances 21 and 22, here shown as condensers. The other sides of the reactances 21 and 22 are connected to the terminals 16 and 18 respectively. The terminals 17 and 19 at the other ends of the filaments are attached to the respective ends of the opposite reactance 23, in this case an inductance coil.

The bulb 13 may contain air highly evacuated. Or else, if desired, the air initially present in the bulb may be replaced by a suitable gas, which may be evacuated. As an alternative I may prefer to fill the bulb with an inert gas such as nitrogen, argon, etc., at normal atmospheric or low pressure.

It is well known that the color of the light emitted, or, more strictly, the wave lengths of the most prominent radiations within the luminous range, depends to a considerable extent upon the character of the substance which is made to glow. I may therefore obtain lights of various colors and characteristics by proper choice of the gaseous atmosphere surrounding the electron-emitting bodies.

It is further well understood that the color produced by a glowing gas is dependent to some extent upon the pressure and I propose to adjust the pressure of the gas in the bulb 5 to suit the result which I desire.

I do not restrict the glowing of my lamp to that which may be produced in gases. I may cause the electron flow to impinge upon solid bodies adjacent to the electron-emitting 10 bodies, more particularly the walls of the tube. By use of special glass, or of other similar substances, for my tube wall, I may produce fluorescence in the wall under the electron bombardment, and employ this as 15 an additional light-giving means.

As seen from the vector diagram of Figure 5, a high alternating potential difference exists between the filaments 14 and 15. The filaments are maintained at an incandescent 20 temperature by current flowing through them, and will produce light as in the case of any incandescent lamp filament. In addition to this the electron flow alternately from one filament to the other will bombard the molecules of environmental gas and cause them to 25 produce light. And the bombardment against the tube walls, or against any solid body exposed within the tube, may cause further luminescence.

30 The spacing of the electron-emitting bodies, whether close or far apart, as well as their shape, will depend upon the size of the lamp, the direction in which the light is to be directed, the voltage and frequency at which 35 the lamp is to operate, the disposition of the supporting structure within the lamp, and the character of the gaseous atmosphere about the hot bodies, among other things. I therefore intend the disposition of the filaments 40 in lamp A of Figure 1 to be purely diagrammatic. I of course do not wish to suggest that the distance between the filaments would be the same as that shown when my invention is embodied in an actual lamp of any size.

45 I intend to indicate that the electron-emitting body may be of any shape or form, whether a rod, sheet, wire, plate or grid, or any other suitable structure. In lamp B I show the bodies disposed in the form of 50 grids 14' and 15', which may be pressed from sheet material, or bent from rod, tubing, or wire. In lamp C I show concentric helical filaments 14² and 15² disposed one about the other to permit the inclusion of considerable 55 filament length within a small tube in close proximity to another filament similarly placed. Other arrangements of the electron-emitting bodies will doubtless suggest themselves to persons skilled in the art, and it is 60 my intention to claim all such as may embody my invention.

In Figure 6 I illustrate a form which I do not consider desirable, but which serves to make plain that my electron-emitting 65 bodies may be maintained hot from separate

current sources, as 10' and 10², while the potential difference between them is due to series resonance in a circuit consisting of the source 10, lines 11 and 12, reactance 23 and opposite reactance 22². The lamp may be of 70 any form, as for example lamp A.

It is immaterial whether the reactance between my electron-emitting bodies is positive (inductance) or negative (capacity), 75 provided reactance elsewhere in the circuit is opposite in character and proper in amount to produce series resonance. Thus in lamps A and B of Figure 1 and lamp C of Figure 2, the reactance between the electron-emitting bodies is positive (inductance 23) so that elsewhere in the circuit negative reactance (capacity 21 and 22 or 21') must be provided. On the other hand, in lamp D of Figure 2 the reactance between the electron-emitting bodies is negative (capacity 23'), so that positive reactance (inductance 21² and 22²) must be supplied elsewhere. 80

Thus it will be evident that the reactance between the electron-emitting bodies may be either negative or positive, but that in any case opposite reactance must be placed elsewhere in the circuit to resonate it. 90

Provided reactance is included in the lamp circuit between the electron-emitting bodies and the source of current, it is immaterial how it is disposed. In lamp A I show my reactance in the form of two condensers 21 and 22, in series with the lamp between the current source and the respective filaments. In lamp B I show only one condenser 21', 95 connected in series between the current source and one of the filaments. From an electrical standpoint either of these forms is permissible, but I prefer the symmetrical disposition of the reactance as shown in lamp A and throughout Figure 2. The reactance may be made up of several units, in series or in parallel, instead of being a single inductance or condenser. 100

105 In Figure 1 I show two of my lamps connected in parallel to the same supply source. In Figure 2 I show four lamps E connected in series with a common inductance 23² and condensers 21³ and 22³. In this form the capacity and inductance must be so adjusted as to resonate the group of lamps in series. It will also be seen that the series of lamps E are themselves connected in parallel with the lamp C and the lamp D. 110

115 Numerous other arrangements of electric connections will doubtless be apparent to skilled persons reading my disclosure, and I intend to claim all such as may involve the principles which I have here made plain. 120

For operation upon polyphase circuits, lamps similarly constructed may embody my invention according to the principles here disclosed, applying the well known circuits for currents of any given phase. 125

130 It will be evident that by using current at

high frequency I obtain the advantages of working under unity power factor, of obtaining greater efficiency and of distributing current much more simply and cheaply than would be possible at low frequency. In addition, I obtain the further advantages over the ordinary incandescent lamp that the size of my lamp is not restricted by the convenient filament size, for the entire lamp will glow and serve as a source of light instead of merely a relatively small filament.

In manufacturing my lamp it would doubtless be possible to construct the inductance coil and the capacities as part of the lamp body or of the lamp mounting, but I do not propose to restrict my invention to any specific lamp structure. I rather desire to protect any structure which involves the principles disclosed.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:

1. The method of electric lighting which consists in maintaining an alternating potential difference between adjacent hot elements of a lamp and producing series resonance in the path of the lamp current, with a reactive potential difference between the elements.

2. The method of electric lighting which consists in producing light through electron discharge by virtue of a potential drop at high frequency across hot elements, due to reactance in series with the elements.

3. The method of electric lighting which consists in electrically heating a plurality of elements within a lamp, maintaining a reactive potential difference between the elements and producing series resonance of the heating current path.

4. The method of electric lighting which consists in maintaining a plurality of separate incandescent current paths in series in a closed system containing a gas at substantially different potentials of high frequency by reactive voltage drop, across the current paths and producing luminescence by current discharge through said gas due to the potential difference between said current paths.

5. The method of electric lighting which consists in resonating a circuit including a plurality of hot current paths, in maintaining the hot current paths in a closed system at substantially different potentials and in producing luminescence from electron emission due to the potential difference.

6. In an electric lamp, a source of current supply, a lamp body containing a plurality of elements adapted to be heated to incandescence, connections from the source to the respective elements, reactance in the connections, and opposite reactance connected from one element to another.

7. In an electric lamp, a source of current supply, a lamp body containing a plurality of filaments each having two contacts, connections from the source to one contact of each filament, reactance in one of the connections and connections, including opposite reactance, joining the other contacts of the filaments.

8. In an electric lamp, a source of current supply, a lamp body containing a plurality of filaments each having two contacts, connections from the source to one contact of each filament, reactance in the connections and connections, including opposite reactance, joining the other contacts of the filaments.

9. In an electric lamp, a lamp body containing a plurality of filaments each having two contacts, current sources connected to the contacts of the respective filaments for lighting each filament, a further current source, connections from the further current source to one contact of each filament, reactance in the circuit, and opposite reactance between the other contacts of the filaments appropriate to produce series resonance in the circuit at the frequency of the further source.

10. In electric lighting, a source of current supply, a lamp body containing two filaments, reactance connected between the filaments, connections from each filament to the current source and opposite reactance between the lamp and the source.

11. In an electric lighting system, a source of current supply, a plurality of lamps each containing a plurality of filaments, connections from the source to one end of each filament in one lamp including reactance between the source and the lamp, connections from the other ends of the filaments of that lamp to the respective ends of the filaments of other lamps so as to place the filaments electrically in series, and opposite reactance between the ends of the filaments of the last lamp.

12. In electric lighting, a plurality of lamps each containing more than one filament, reactance connected at its respective ends to one end of each filament, a source of current supply, and connections, including opposite reactance, to the supply from the other end of each filament placing the lamps electrically in parallel.

13. The method of producing light, which consists in setting up series resonance in a current path including reactance and in impressing the reactive voltage drop across the environmental gas in a closed system.

14. The method of producing light, using electrodes in a closed system, which consists in heating the electrodes, in setting up series resonance in a current path including reactance and in impressing the reactive voltage drop between the electrodes.

15. The method of producing a discharge across a tube from a source at a voltage too low to send current across the tube, which ¹⁰ consists in producing series resonance and in connecting the tube between points of maximum difference in displacement of voltage with respect to current.

16. The method of producing light, using ¹⁵ a tube having elements, which consists in passing alternating current successively through a reactance, to a hot element of a tube, through an opposite reactance and to another element of the tube.

20 17. In an electric circuit, a tube having elements, a source of alternating current, circuit connections from the source to the elements and means for producing series resonance in the circuit and for producing a ²⁵ reactive potential drop between the elements.

18. In an electric circuit, a tube having elements, means for heating an element, a source of alternating current, circuit connections from the source to the elements and means ³⁰ for producing series resonance in the circuit and for producing a reactive potential drop between the elements.

19. An electric circuit including in series in the order named, a source of alternating ³⁵ current at high frequency, a reactance, an element of a tube, an opposite reactance and another element of the tube.
